UNITED STATES PATENT OFFICE.

AUSTIN ADAMS, OF NEW YORK, N. Y.

LATCH.

SPECIFICATION forming part of Letters Patent No. 595,427, dated December 14, 1897.

Application filed April 20, 1897. Serial No. 633,059. (No model.)

To all whom it may concern:

Be it known that I, AUSTIN ADAMS, a citizen of the United States, and a resident of New York, in the county and State of New York, 5 have invented a certain new and useful Latch, of which the following is a specification.

My invention relates to latches for fastening and unfastening doors for refrigerators and other structures where tight swinging 10 doors are required, and has for its object to provide a latch simple in construction, inexpensive in manufacture, and efficient in practical use.

My invention consists in the construction, 15 arrangement, and operation of the parts hereinafter set forth.

Figure 1 is a plan view of my latch. Fig. 2 is a plan, and Fig. 3 a perspective view, of my keeper or catch; and Figs. 4 and 5 are 20 views in detail of my unlocking device and my latch-handle, and Fig. 6 is a view in section of another latch constructed according to my invention.

Like letters of reference indicate like parts 25 in all the views.

In the drawings, B is an arched laterally-projecting horizontal bracket which supports the latch A'. This latch is secured on the inner end of a shaft B', which is journaled in 30 a bearing in the outer end of said bracket B. On the outer end of said shaft B' is secured a preferably weighted handle A, which is adapted to rotate the shaft and thereby operate the latch.

C represents the keeper, which is preferably secured to the door-jamb. This keeper consists of a tubular engaging portion the longitudinal axis of which extends at right angles to the plane or face of the support thereof, 35 provided on its outer engaging end with an inclined spiral edge C', extending upwardly and rearwardly. Commencing at the point C⁴ this edge C' forms the rear edge of a spiral slot C³, whose anterior or front edge C⁴ is 40 formed by the part C² of the outer end of the tubular keeper. This spiral slot C³, as clearly shown in the drawings, extends downwardly and rearwardly, and the anterior and posterior edges of which form bearing surfaces or 45 edges which are engaged by the latch in securing and releasing the door. Extending through the axial center of said tubular

keeper to the opposite side of the door is a rotatory rod or shaft D², on the outer end of which is an operating finger or projection D'. 55 On the inner end of said shaft D² is secured an operating-handle D, which is adapted to be operated from the interior of the compartment for locking or releasing the latch A'. It is clear from the construction illustrated 60 that when the latch is in positive engagement with the spiral slot C³ and the operating finger or projection is rotated in one direction by the operating-handle D the edge d³ will impinge against the part a³ of the pivoted or 65 swinging latch A' and move the same toward the inner end of the spiral slot, thereby securely fastening the door. If the operating-handle is turned in a direction opposite to that above described, the edge d² of the operating-finger D' engages the opposite side of the part a³ of the pivoted latch and forces the 70 same upwardly in the spiral slot C³, thereby releasing the door from engagement with the keeper. 75

It is evident that when the latch engages the spiral slot C³ in fastening the door one side of the portion a³ of such latch will bear against the anterior edge C⁴ of the spiral slot C³, and as such latch is forced around 80 such slot it will be guided by the inclined edge C⁴ downwardly and rearwardly, thereby wedging or forcing the door to which the latch is secured into engagement with the door-frame. On the other hand, when this operation is reversed and the latch is to be released by the handle A or B the opposite side of the part a³ of the latch rides up the posterior edge C' of the spiral slot, which movement would be upwardly and forwardly, thereby releasing 90 the latch from the spiral slot and at the same time forcing outwardly the latch and door to which it is fastened or secured. It will be observed, therefore, that the operation of engaging the latch with the keeper not only fastens the door, but also forces or crowds the door into its seat, while the operation of releasing the latch from the keeper not only releases the latch, but forces the door out of engagement with its seat in the door-frame. 95 100

It is manifest that various omissions of some particulars could be made without materially affecting the essential features of my invention or the operation of the remaining parts,

and I do not therefore wish to be limited to the specific structural details of the organization herein set forth. Obviously the elements of the structure described may be located at an angle to the plane in which they are shown. I accordingly use the words "horizontal," "vertical," and the like in a relative sense.

In operation the pivoted or swinging latch 10 A' upon striking the inclined edge C' will commence to rotate, and upon engaging the spiral slot C³ will have made almost an entire revolution. In case the door is slammed to this 15 action will take place without touching the handle at all. By turning the handle still farther around the door will be wedged up tight.

My tubular catch or keeper may be provided with suitable supporting or attaching 20 means, as the vertical plate C¹⁰, or, for example, the end of this keeper may be screw-threaded and directly screwed into the door-jamb, as shown in Fig. 6.

The end of the shaft B' may be provided 25 with a pin B⁷, which works in a slot A⁷ of the handle A, loosely mounted on the shaft A, the said pin stopping the handle from revolving any farther than the ends of the slot. When the shank or lever a³ strikes the slot or 30 groove in the keeper, it is caused to follow freely the incline of the groove until the pin B⁷ strikes the end of the slot A⁷ in the sleeved end of the handle A. This quick motion causes the handle to fly up or revolve on the 35 shaft and having play to go to the end of the slot, and thus overweights the parts A' a³ and causes the portion a³ to positively engage the keeper and enter the groove C³ sufficiently to interlock the two members of my keeper. 40 The pin B⁷, being caused to strike the end of the slot A⁷ by the said part a³ turning in the groove, picks up the weighted handle and causes it to travel as far around the shaft as the length of the slot will permit.

45 As it is evident that many changes in the construction and relative arrangement of parts might be resorted to without departing from the spirit and scope of my invention I would have it understood that I do not restrict myself to the particular construction and arrangement of parts shown and described, but that such changes and equivalents may be substituted therefor, and that

What I claim as my invention is—

50 1. In a fastening device, the combination, with a tubular keeper, the longitudinal axis of which is substantially at right angles to the plane or face of the support thereof, provided with a spirally-inclined edge and a spiral slot having a downwardly and rear-

wardly inclined anterior face, of a relatively movable latch consisting of a pivoted or swinging arm whereby a door may be crowded into its frame by means of the engagement of the pivoted latch with the anterior face of said slot.

2. In a fastening device, the combination, with a pivoted or swinging latch, of a tubular keeper the longitudinal axis of which is substantially at right angles to the plane or face of the support thereof, provided with a spiral slot the rear edge of which inclines downwardly and rearwardly, against which the latch works, whereby upon releasing the latch, the door is forced open, substantially as described.

3. In a latching device the combination, of a pivoted or swinging latch, of a tubular keeper, the longitudinal axis of which is substantially at right angles to the plane or face of the support thereof provided with a spiral slot extending rearwardly, said latch engaging the anterior and posterior edges of such slot, whereby in locking the latch the door is crowded into its seat, and, in releasing such latch, the door is forced open, as specified.

4. In a latching device the combination, with a rotating or swinging latch, a tubular keeper having a spiral slot engaged by said latch of a rotating shaft passing axially through said tubular keeper to the opposite side of the door, said shaft provided at its forward end with an operating finger or projection, and at its opposite end with an operating-handle, whereby the latch may be fastened or released from either side of the door, as specified.

5. A latch-keeper having attaching means and a tubular portion provided with a spirally-inclined edge and a spiral slot cut through the wall thereof and extending rearwardly and downwardly, the longitudinal axis of said tubular portion extending substantially at right angles to the plane or face of the support thereof, as specified.

6. In a latch consisting of two members respectively secured to a door and jamb, the combination, with a keeper provided with a spirally-inclined edge and a spiral groove, of a pivoted or swinging latch, and a handle having a limited rotary movement with respect to said latch, as specified.

In testimony of the foregoing specification I do hereby sign the same, in the city of Washington, in the District of Columbia, this 7th day of April, A. D. 1897.

AUSTIN ADAMS.
